CLOSURE

Martha P. Keith, Brookline, Mass.

Application June 30, 1934, Serial No. 733,230

15 Claims. (Cl. 215—63)

My invention relates to closures for jars, bottles, flasks and like containers of the type wherein a cap or shell, threadedly engageable with the open end of the container, has a central orifice closable by a pivoted or hinged lid.

In this type of closure the contents of the container, such for instance as cream and scented compounds, have been exposed to the manual touch and defacement of a potential purchaser's finger, when the orifice has been disclosed by opening the lid. Certain objects of the present invention, therefore, are, without removal of the cap, to render the contents visible under such circumstances and protect the latter from manual contact, removal or derangement, by a transparent member that is inexpensive, secure, and protective of the scent of the contents.

Heretofore the skirt portion of the cap has been rendered unsightly by the resultant external shoulder or shoulders occasioned by the formation of the internal continuous or broken attaching thread, and an object of the present invention is to inexpensively prevent this result.

Additional objects are to provide means for scraping away such contents as may accidentally accumulate at points adjacent the orifice of the cap; to so thoroughly seal at all times and under all circumstances both the cap and the cover as to prevent the evaporation or odoral escape of the container contents; to provide means within the lid for an advertising display when the lid is elevated, and to attain all the above enumerated objects in an inexpensive, and secure structure.

With the above and other objects and advantages in view, the invention consists of an arrangement of parts more fully disclosed in the detailed description following, in conjunction with the accompanying drawing, and more specifically defined in the claims appended thereto.

In the accompanying drawing forming a part of this specification,

Figures 1 and 2 are a side elevation and a top plan view respectively of a container engaged with my novel closure,

Figure 3, an enlarged section of the same taken on line 3—3 of Figure 2,

Figures 4 and 5, detail perspective views of the transparent member and the lower sealing ring respectively,

Figure 6, a fragmentary perspective view of the lid attaching rim, and

Figure 7, a fragmentary section on line 7—7 of Figure 2.

Similar characters of reference indicate similar parts throughout the views.

As shown in the drawing the container is a jar comprising a body portion 2 and a neck portion 3 provided with the usual external screw thread 4, either continuous or broken.

The container closure includes a shell or cap 7 drawn up from thin sheet metal, comprising a flat top 8, a cylindrical skirt or side 9, and an inwardly directed upturned annular flange 10 upon the bottom of the skirt tightly embracing the lower margin of a cylindrical metallic lining ring 11 provided with an internal thread 12. Interposed snugly between the top of the lining ring and the top of the cap is a flat sealing ring 14 provided in its upper face with a circular recess 15 and composed preferably of paraffin paper.

The top of the jar neck portion 3 is flat and terminates at a point below the ring 14, affording an annular space 16 for the reception of a detachable flexible guard member 17, shown in detail in Figure 4, comprising an annular frame 18, preferably of cardboard, whose opening is closed by a circular sheet 19 of cellophane or other transparent material pasted at its peripheral margin to the top of the frame.

In a central opening 20 in the top 8 of the cap is fixed an attaching rim 22 comprising an annular body 23 provided with horizontal marginal clamping flanges 24 and 25 adapted to embracingly engage the top and bottom of the cap top respectively. The flange 25 is seated in the recess 15 of the ring 14. Integral with the outer periphery of the flange 24 is a vertical annular lip 26, provided with a segmental recess 27, at each side of which hinge sleeves 28 are integral with or soldered to the lip and embrace a pintle 29, as shown in Figure 6.

A circular lid 31 comprises a convex central body portion 32 and a flat annular marginal portion 33 provided with an inturned peripheral flange 34 embracing the peripheral margin of an annular attaching lug portion 36 of a depending guide flange 37 inset from the periphery of the lid and adapted, when the lid is depressed, to slidably engage the portion 23 of the attaching rim 22 and scrape therefrom any of the jar contents accidentally adhering to the rim.

A flat sealing ring 38 is frictionally retained by and between the guide flange 37 and the edge of the peripheral flange 34 of the lid, assists to prevent the access of air to the jar contents when the lid is closed.

A display disk 39 of cardboard or other suitable material, preferably laminated with cellophane

- to protect printed advertising matter, has its edge frictionally engaging the flange 37 and is pressed against the marginal portion 32 of the lid by a bezel or ring 41 frictionally engaging the 5 flange 37.
- A hinge sleeve 43 integral with or fixed to the periphery of the lid 31 embraces the hinge pin 29 between the sleeves 28. A thumb nail projection 45 upon the lid diametrically opposite the sleeve 43 serves to assist the manual elevation of the lid which is normally held in closed position by a snap projection 46 upon the flange 37 engaging a notch 47 in the flange 22.
- In use the container may be filled flush with the top of the neck portion 3, and the detachable guard member 17 has its frame 18 resting upon the latter with its attached transparent window sheet 19 guarding the contents against the touch of the prospective purchaser who has manually lifted the lid 31. After the purchase has been made the cap 7 may by unscrewing be removed, the member 17 be withdrawn and discarded to facilitate access to the user, and the cap be replaced by screwing it down until the sealing ring 14 rests upon the top of the jar neck.
- By placing the screw thread 12 upon the lining ring 11 rather than forming the engaging thread upon the cap skirt the latter is undefaced and unweakened.
- The annular lip 26 upon the flange 24 of the lid attaching rim 22 forms a guard and seat for the periphery of the lid. The flange 37, inset from the periphery of the lid not only guides the lid centrally of the attaching rim 22 as the lid is depressed but serves as a scraper in the manner hereinabove mentioned.
- Throughout the specification and claims the word "thread" is intended to include a spiral thread, either continuous or broken, or a spirally disposed plurality of studs or projections.
- I claim:—
1. In a closure for a container having a threaded upper portion, a cap including a top provided with a central opening, and a cylindrical skirt, an attaching rim fixed in said opening, a lid for closing the opening, and a cylindrical lining ring in said skirt provided with a thread adapted to engage the threaded portion of the container.
  2. In a closure for a container, a cap including a top provided with a central opening, and a skirt, an attaching rim fixed in the top in the opening, a lid on the rim for closing the opening, and a transparent guard member supported by the skirt below said rim.
  3. In a closure for a container, a cap including a top provided with a central opening, and a skirt, means supported by the top for closing the opening, a lining ring fixed to the skirt, and a transparent guard member comprising an annular frame engaging the lining ring, and a transparent sheet fixed to the frame below the closing means.
  4. In a closure for a container having a threaded upper portion, a cap including a top provided with a central opening, and a depending skirt, a lid supported by the top adjacent the opening, a lining ring fixed in the skirt provided with an internal thread adapted to engage the threaded portion of the container, a sealing ring in the cap resting upon the lining, and a detachable transparent guard member engaging the sealing ring and the lining ring and extending transversely of the opening.
  5. In a closure for a container having a threaded upper portion, a cap including a top provided with a central opening, and a skirt, a lid supporting the top for closing the opening, a sealing ring within the cap abutting against the top, and a lining fixed to the skirt and abutting against the sealing ring provided with a thread engageable with the threaded portion of the container.
  6. In a closure for a container having a threaded upper portion, a cap including a top provided with a central opening, and a skirt, a lid for the opening, a lining ring abutting against the skirt provided with a thread adapted to engage the threaded portion of the container, and an upturned flange upon the bottom of the skirt embracing the lower margin of the lining ring.
  7. In a closure for a container, a cap including a top provided with a central opening, and a skirt, an attaching rim comprising an annular body in the opening, and horizontal clamping flanges upon the top and bottom of the body embracing the cap top, and a lid supported by the top flange adapted to close the opening.
  8. In a closure for a container, a cap including a top provided with a central opening, and a skirt, a lining ring fixed to the skirt and provided with a thread, a flat sealing ring interposed between the upper end of the lining ring and the cap top and provided in its upper face with an annular recess, an attaching rim comprising an annular body in the opening abutting against the edge of the cap top, a clamping flange upon the bottom of said body seated in the annular recess, and a clamping flange upon the top of the body overlapping the cap top, and a lid supported by the top flange adapted to close the opening.
  9. In a closure for a container, a cap including a top provided with a central opening, and a skirt, an attaching rim comprising an annular body in the opening, a clamping flange integral with the top of the body overlapping the cap top, a flange integral with the bottom of the body engaging the bottom of the cap top, and a vertical annular guard lip upon the periphery of the overlapping flange, and a lid hingedly supported by the last mentioned flange and adapted to be seated in the guard lip.
  10. In a closure for a container, a cap including a top provided with a central opening, and a skirt, an attaching rim fixed to the top in said opening including an upright peripheral lip, hinge sleeves upon the lip, a lid, a hinge sleeve upon the lid, a pintle connecting the sleeves, a depending annular guide flange fixed to the lid and inset from the periphery thereof adapted to slidably engage the attaching rim when the lid enters the opening.
  11. In a closure for a container, a cap including a top provided with a central opening, and a skirt, an attaching rim fixed to the top in said opening, hinge sleeves upon the rim, a pintle in the sleeves, a lid comprising a circular body, an inturned peripheral flange upon the body, an annular lug embraced by the flange, a guide flange depending from the lug adapted to slidably engage the attaching rim, a sealing ring interposed between the guide flange and inturned peripheral flange, and a hinge sleeve upon the body of the lid engaging the pintle between the first mentioned hinge sleeves.
  12. In a closure for a container, a cap including a top provided with a central opening, and a skirt, an attaching rim fixed to the top in said opening, hinge sleeves upon the rim, a pintle in the sleeves, a lid comprising a circular body, an inturned peripheral flange upon the body, an annular lug

embraced by the flange, a guide flange depending from the lug engageable with the attaching rim, a hinge sleeve upon the body engaging the pintle, a display disk in the cover abutting against the 5 guide flange and a bezel engaging the guide flange and display disk.

13. In a closure for a container, a cap having an opening, an attaching rim, parts on said rim engaging the edge of said opening for locking the 10 rim thereto, and a lid mounted on said rim for closing said opening.

14. In a closure for a container, a cap having

an opening, an attaching rim, flanges on said rim engaging the edge of said opening for locking the rim thereto, and a lid hingedly mounted on said rim for closing said opening.

15. In a closure for a container, a cap construction including a top provided with an opening, a hingedly mounted lid extending over said opening, and a transparent guard member mounted in the cap below the lid and extending transversely of the opening.

MARTHA P. KEITH.
